THERMOSTATIC CIRCUIT CONTROLLER

Robert J. Parsons, Schenectady, N. Y., assignor to
 Consolidated Car-Heating Company, Inc., Albany, N. Y., a corporation of New York

Application May 9, 1934, Serial No. 724,716

5 Claims. (Cl. 175—375)

This invention relates to electricity, more especially to circuit controllers, and particularly to circuit controllers governed by temperature, commonly known as thermostatic circuit controllers.

A principal object of this invention is to produce a device of the type specified which will be compact, easy to adjust, simple and inexpensive to manufacture, particularly free from a tendency to get out of order, and certain and powerful in its action.

Other objects and advantages will appear as the description of the particular physical embodiment selected to illustrate the invention progresses, and the novel features will be particularly pointed out in the appended claims.

In describing the invention in detail and the particular physical embodiment selected to illustrate the invention, reference will be had to the accompanying drawing and the several views thereon, in which like characters of reference designate like parts throughout the several views, and in which:

Figure 1 is a front elevational view of a panel with a thermostatic circuit controller of applicant's invention in place thereon; Fig. 2 is a cross-sectional view of the device on the plane indicated by the line II—II of Fig. 1, viewed in the direction of the arrows at the ends of the line; Fig. 3 is a schematic or diagrammatic illustration of a circuit with which applicant's thermostatic circuit controller is advantageously used.

In the figures, numeral 1 designates a panel or mounting member upon which applicant's device may be positioned. This panel is made of an insulating material as is usual.

Attached to the panel 1, preferably by means of screws, as 2, is the magnet bar 3 made of magnetic material. The magnet bar 3 supports the electro-magnet 4, having the pole piece 5, by means of screws as 6.

Cooperating with the electro-magnet 4 and its pole piece 5 is the latch lever 7, pivoted at 8, and formed with the latch shoulder 9 at one end, and adjacent thereto, the contact face 10. Intermediate the pivot 8 and the latch shoulder 9 is the stop shoulder 11. To the right of the pivot as viewed in Fig. 1, the pivot lever 7 is formed with a non-magnetic facing 12 to prevent the latch from sticking to the pole 5 of the electro-magnet 4. The latch lever 7 to the right of the pivot 8, as viewed in Fig. 1, is also formed with depressed spring seat 13 for receiving the end of an expandable spring, or biasing means 14 the other

end of which seats in the depressed spring seat 15 of the member 3. The latch lever 7 also carries the manual grasping insulating button 16 provided with the finger guard 17 and attached by means of the screw 18 to the lever. This manual grasping button 16 enables a manual operation of the latch lever 7 without danger of receiving electric shock.

The magnet bar 3 also supports the pivoted latch pivot supporting arm 19 attached as by means of screws 20. This arm 19 also supports the contact post and pivot lever stop 21.

A contact finger 22 is positioned to engage the contact face 10 and contact face 10', being latched by the latch shoulder 9, and resiliently supported by the contact finger carrying arm 23. The resilient support is formed by a bolt 24 having a head 25 on one side of the contact finger carrying arm 23 after passing through the arm and the contact finger surrounded by the contact finger spring 26 held in place by a washer 27 and a cotter pin 28. This construction is such that if contact finger 22 is latched by latching shoulder 9 and contact finger carrying arm 23 moves to the left, as viewed in Fig. 1, then the contact finger 22 will not be injured.

The contact finger carrying arm 23 is mounted upon the shaft 29 and is clamped thereon by having one end bifurcated and a bolt 30 passing therethrough so as to draw the parts of the bifurcated ends together so as to fasten the member firmly upon the shaft 29. The contact finger carrying arm 23 also has formed, as an extension thereof, the contact carrying arm stop 31 positioned to abut the stop 32, formed as a projection upon the shaft carrying plate 33.

The shaft carrying plate 33 is formed with a bearing 34 through which the shaft 29 passes. The shaft 29 extends backwardly from the plate 33, as viewed in Fig. 1, or to the left of the panel 1, as viewed in Fig. 2. At its farther end, one end of a spirally wound bi-metallic thermo-responsive element 35 is attached, as by means of the screw 36. The bi-metallic member 35 surrounds the shaft and the other end is attached relatively to the plate 33 by means of the clamping bolt 37 which passes through the plate 33, the panel 1 and the inner end 38 of the bi-metallic member, and is then provided with a threaded end 39 and a nut 40 whereby the inner end of the bi-metallic member is securely held in place.

The bi-metallic member 35 is so positioned upon the shaft 29 and so held, that when the temperature is relatively high, the shaft 29 is turned so as to bring the contact finger carrying

arm 23 and the contact finger 22 into position to be latched by the latching shoulder 9 of the latching lever 7. If the latch is in the position as shown in Fig. 1 when this movement takes place the end 41 of the contact finger 22 will engage the sloping face 42 of the latching lever 7 and depress it. After the contact finger 22 has passed beyond the shoulder 9 the spring 14 will force the latch lever 7 up so that the shoulder 9 engages with the end 41 of the contact finger 22 and thereby holds it in latched position.

If after the contact finger 22 becomes latched, as shown in Fig. 1 in full lines, the temperature falls to a relatively lower temperature then the shaft 29 will be twisted by the bi-metallic member 35 so as to tend to move contact finger 22 to the left as viewed in Fig. 1. If this continues, the contact finger carrying arm 23 will, at its lower end, separate from the contact finger 22 bending contact finger 22. This separation is possible because of the spring connection between the contact finger carrying arm 23 and the contact finger 22.

If the contact finger 22 is latched and it is desired to release it, one may manually grasp the manually grasping button 16 and force it upwardly against the spring 14 so that contact finger 22 may be released from the latch shoulder 9, if the temperature is such that the shaft 29 is moved to a position such that contact finger 22 should be to the left of its position as shown in full lines in Fig. 1.

In Fig. 3 a circuit is shown employing the thermostatic circuit controller of Figs. 1 and 2. In this figure 38 designates a manually operable switch which is shown in the closed position so that current may flow from the positive terminal of a source of potential by wire 44 through manually operable switch 43, wire 45, resistance 46, wires 47 and 48, coil of electro-magnet 49, wire 50, electro-magnet 4, and wire 51 to the negative terminal of the source of potential. Current flowing in the above traced path energizes electro-magnet 49 and causes its armature 52 to be raised and held raised so that a circuit is formed as follows: positive terminal of a source of potential, wire 44, switch 43, wires 45 and 53, armature 52 and wire 54, through resistances 55, 56 and 57 to the negative terminal of the source of potential. Devices designated 55, 56 and 57 are shown as heating coils and may well be the heating coils used to heat a space within which the thermostatic device designated as a whole by T may be placed and in which a thermostatic device designated by S may also be placed.

When the electro-magnet 49 is energized and its armature 52 is raised the latch 7 is also raised toward the electro-magnet 4 so that the latch would then stand in practically a horizontal position with its latch shoulder 9 out of position to engage with the contact finger 22.

If the heat generated by the coils 55, 56, and 57 reaches the bi-metallic thermo-responsive member 35 of the device T, it will cause the contact finger 22 to move to and become latched, as shown in dotted lines in Fig. 3. This would occur because when contact finger 22 touches contact post 21, a circuit would be formed in shunt of the electro-magnet 49 from wire 47, through wires 58 and 59, latch 7, pivot support 19, post 21, contact finger 22 and wire 60 to the negative terminal of the source. This path is a shunt path which is of such resistance as compared with the circuit through the electro-magnet 49 that electro-magnet 49 and electro-magnet 4 would

both become de-energized and armature 52 would drop, cutting off the circuit of the heating coils 55, 56 and 57, and latch lever 7 would be pushed upwards, so that shoulder 9 would be brought up so as to latch contact finger 22 in its then position. The parts would then remain latched until the thermostatic device had cooled off and latch 7 has been moved upwardly against the spring 14 manually by the manual grasping button 16.

Applicant has also shown another means in Fig. 3 by which current may be cut off from the coils 55, 56 and 57. This is the thermostatic device S, which may also be positioned to be affected by the heat from the heating coils. When the temperature rises high enough the thermostatic device S moves the circuit controller arm 61 into contact with the contacts 62 and 63 thereby forming a shunt path from wire 47 through wires 58 and 64, contact 62, controller arm 61, contact 63 and wire 65 to the negative terminal of the source of potential. This path also would cause a de-energization of electromagnets 49 and 4 and would thereby cause armature 52 to drop and current be cut off from the heating coils 55, 56 and 57, but as soon as the temperature fell the circuit controller arm 61 would be withdrawn from in contact with 62 and 63 and current of sufficient value to energize electromagnets 49 and 4 would again flow so as to lift armature 52 and raise latch 7 against the tension of the spring 14 so that unless the temperature were high enough to cause thermostatic device T to so operate as to bring contact finger 22 into contact with stop 21 the relations of the parts would be re-established automatically.

Although I have particularly described one particular physical embodiment of my invention and explained the operation, construction and principle thereof, nevertheless I desire to have it understood that the form selected is merely illustrative, but does not exhaust the possible physical embodiments of the idea of means underlying my invention.

What I claim as new and desire to secure by Letters Patent of the United States, is:

1. In a thermostatic switch, in combination: a rotatable shaft; a bi-metallic thermo-responsive strip spiralled about the shaft, having one end connected to the shaft and the other end fixed; a contact finger adapted for governing a circuit mounted on the shaft to move in one direction therewith; a latch positioned to engage and latch the contact finger; a pivot intermediate the ends of the latch; a compression spring having one end bearing on the portion of the lever on the other side of the pivot from the latch and having its other end bearing against a fixed abutment; manual means for moving the latch out of the path of the contact finger; electro-magnetic means for moving the latch out of the path of the contact finger.

2. In a thermostatic switch, in combination: a rotatable shaft; a bi-metallic thermo-responsive strip spiralled about the shaft, having one end connected to the shaft and the other end fixed; a contact finger adapted to control a circuit; means for mounting said contact finger upon said shaft whereby the contact finger is positively rotated in one direction of movement of the shaft and resiliently in the other direction whereby the contact finger may remain stationary for a predetermined movement of the shaft; and means for the contact finger to contact with when in one position whereby thereafter the con-

tact finger is held in rotated position regardless of the action of the rotatable shaft.

3. In a thermostatic switch, in combination: a contact finger; a contact post; thermo-responsive means for moving the contact finger into and away from contact with the contact post; a latch positioned to latch the contact finger in contact with the contact post; a pivot for the latch; a stop for the latch; electro-magnetic means for moving the latch out of position to latch the contact finger; and resilient means positioned to act on the latch to move it into position to latch the contact finger.

4. In a thermostatic switch, in combination: a contact finger; a contact post; thermo-responsive means for moving the contact finger into and away from contact with the contact post; a latch positioned to latch the contact finger in contact with the contact post; a pivot for the latch; a stop for the latch; manually operable means for moving the latch into position to unlatch the contact finger and resilient means to move the latch into position to latch the contact finger.

5. In a thermostatic switch, in combination: a contact finger; a contact post; thermo-responsive means for moving the contact finger into and away from contact with the contact post; a latch positioned to latch the contact finger in contact with the contact post; a pivot for the latch; a stop for the latch; biasing means for the latch; an electro-magnet positioned to cooperate with the latch and move the latch out of latching position when energized; a circuit for the electro-magnet containing a source of potential; and means for closing the circuit whereupon the latch is moved out of latching position by the energization of the electro-magnet; a shunt for the circuit through the electro-magnet including the contact finger and the contact post whereby when the contact finger and contact post are in engagement current is shunted from the electro-magnet and the latch is moved into latching engagement by the biasing means; and manually operable means for moving the latch into position to unlatch the contact finger and thereby break the shunt.

ROBERT J. PARSONS.
